DESIGN.

F. MANKEY.

MOLDING.

No. 16,523.

Patented Feb. 16, 1886.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 16,523, dated February 16, 1886.

Application filed November 2, 1885. Serial No. 181,721. Term of patent 7 years.

To all whom it may concern:

Be it known that I, FREDERICK MANKEY, of Williamsport, Lycoming county, Pennsylvania, have invented and produced a new and original Design for Moldings, of which the following is a specification, reference being had to the accompanying photograph, forming part hereof.

Upon the surface of the molding are triangular pyramidal elevations A. Between said elevations are channels B C, extending diagonally across the surface in alternately opposite directions. Each alternate pyramid has a side, D, parallel to the edge of the molding. The angle of inclination of said side with reference to the surface of the molding is greater

than that of the remaining inclined sides of the pyramid.

I claim—

The design for a molding, substantially as herein shown and described, which consists in the pyramidal elevations A and the channels B C, each alternate pyramid having one side parallel to the edge of the molding, the said pyramidal elevations showing on their surfaces a different grain-marking from that which appears in said channels.

FREDERICK MANKEY.
